UNITED STATES PATENT OFFICE.

CHARLES CHAPPELLE, OF OKLAHOMA, OKLAHOMA, ASSIGNOR OF ONE-HALF TO DOCTOR JOHN HAYDEN, OF OKLAHOMA, OKLAHOMA.

PNEUMATIC RAILWAY-SWITCH.

1,130,477.

Specification of Letters Patent.

Patented Mar. 2, 1915.

Application filed May 9, 1912. Serial No. 696,170.

To all whom it may concern:

Be it known that I, CHARLES CHAPPELLE, a citizen of the United States, residing at Oklahoma city, in the county of Oklahoma and State of Oklahoma, have invented certain new and useful Pneumatic Railway-Switches, of which the following is a specification, reference being had to the accompanying drawings.

10 This invention has reference to the art of railways, and more particularly to the art of railway switches.

An object of the invention is to provide improved means whereby the tongue of a 15 switch may be shifted from one position to the other by suitable operating means carried by or operating in conjunction with some portion of a car or train.

Other objects and advantages of the 20 invention will be set forth in the ensuing description.

Referring to the accompanying drawings, which show one embodiment of the invention in practical form:—Figure 1 is a plan view of a portion of railway, in connection with which the invention is shown in use. Fig. 2 is an enlarged plan view, partly in section, of parts shown in Fig. 1. Fig. 3 is a side elevation of a railway track and 25 the trucks of a car, showing the invention in use in connection therewith. Fig. 4 is a sectional view of a certain cylinder and its piston, in the same direction as Fig. 3. Fig. 5 is a sectional view taken on the line 5—5 30 of Fig. 3, but showing no parts in the rear of the line A—A. Fig. 6 is a perspective view of a bracket for supporting certain tripping means carried by the car-trucks. Fig. 7 is a perspective view, in different 35 direction, showing a tripping-arm. Fig. 8 is a sectional view of a check-valve.

Like characters of reference designate like parts throughout all the figures of drawings.

40 Suitably positioned on the outer sides of the track-rails 9 and 10 are cylinders 11 and 12, respectively, which are supported by brackets 13 secured by bolts 14 to the webs 15 of said rails.

45 Within each of the cylinders 11 and 12 is a piston 16, which is made hollow to allow room for a tension spring 17. This spring 17 has one of its ends attached to the front or closed end of the piston 16 by an eye-

5 bolt 18, and its other end to the rear end of the cylinder by a similar eye-bolt 19, and said spring yieldably holds said piston to the rear or normal end of its throw in said cylinder.

Each of the cylinders 11 and 12 is provided in its upper wall with a groove 20, up through which a stud 21 on the piston 16 projects, this groove being straight and parallel with its cylinder for a major portion of its length and then terminated in a spiral 60 22 so that said stud and piston may be driven forward by a suitable projection from a car or train and then revolve to avoid further forward movement by said projection. In further arrangement, cylinders 23 and 24 are located in juxtaposition to the switch, the cylinder 23 being connected with the cylinder 11 by a pipe-line 25 and the cylinder 24 with the cylinder 12 by a similar pipe-line 26. The cylinder 23 is 65 provided with a piston 27 and the cylinder 24 with a piston 28, the stems 29 and 30, respectively, of these pistons passing through the guard-rails 31 and 32 in position to have their ends 35 and 36 act against opposite 70 sides of the switch-tongue 37. To hold the pistons 27 and 28 at the normal or initial ends of their cylinders, the stem of each piston is embraced by a compression helical spring 38 which is interposed between said 75 piston and the opposite end of said cylinder.

Each of the pipe-lines 25 and 26 is provided with a check-valve 39 to check the back flow of air from the cylinders 23 and 24 to the cylinders 11 and 12, each check-valve having a hinged gate 40 adapted to close against a seat 41, as shown in Fig. 8. The gate 40 is provided with a very small opening 42, through which the air which 90 is placed under compression between the check-valves 39 and the cylinders 23 and 24 may slowly leak to relieve the compression.

In operation, the piston 16 of one of the cylinders, say the cylinder 11, is driven forward by a suitable projection on the car or car-trucks, thereby setting up pressure of the air in the pipe-line 25 and against the piston 27 in the cylinder 23. Since the pipe-lines 25 and 26 must be small in order to 100 avoid excessive range of expansion of the contained air, the compression between the piston 16 of the cylinder 11 and the piston 105

27 of the cylinder 23 may not instantly equalize; so that when said piston 16 is moved by a car at high speed it may instantly set up high pressure and as quickly 5 release it by return to normal position, leaving the piston 27 and switch-tongue 39 unmoved or only partly moved. But the check-valve 39 traps the air under compression in the pipe-line 25 and cylinder 23 and 10 allows said compression to release only by leakage of air through the small opening 42 aforesaid, thus allowing the compression to move the piston 27 and switch-tongue 37 their full throw.

15 In arranging the vehicle portion of the apparatus, a suitable tripping-arm 43 is pivoted between brackets 44 depending from the frame of the car-trucks, these brackets having holes 45 in which the shaft 46 of 20 said tripping-arm is journaled. The hub portion of the tripping-arm 43 is provided with a stop 47 which plays in an arc-shaped recess 48 in one of the brackets 44 and is adapted to abut either end of said recess to 25 limit the movement of said tripping-arm. For operating the tripping-arm 43, its shaft 46 is provided with a gear-pinion 49 which receives motion from gear-teeth on the lower end of a piston-rod 50 of a piston 51.

30 The piston 51 is contained within a cylinder 52, which is bolted to the frame of the car-trucks, and said piston may be moved by compressed air from the train-pipe of the car or train in order to swing the tripping- 35 arm 43 into or out of tripping position.

Having thus described this invention, I claim:

1. A pneumatically operable railway switch, consisting of a switch located at the 40 intersection of railway lines, of a switch tongue associated with said switch and adapted to be urged to normal positions with respect to each line, cylinders located in juxtaposition with said switch, pistons operable in said cylinders and adapted to 45 operate against the tongue alternately, cylinders located remotely from the first named cylinders, pistons operable therein for creating air pressure, means for operating said last named pistons, means for positioning said pistons normally, and an air-line communicating with each set of cylinders.

2. A pneumatically operable railway 55 switch, consisting of a switch located at the intersection of railway lines, of a switch-tongue associated with said switch and adapted to be urged to normal positions with respect to each line, cylinders located in juxtaposition with said switch, spring-actuated pistons operable in said cylinders and adapted to operate against said tongue alternately, cylinders located remotely from the first named cylinders, spring-actuated 60 pistons operating therein, means carried by

the second named pistons for urging them to pressure-creating positions, and an air line communicating with each set of cylinders.

3. A pneumatically operable railway 70 switch, consisting of a switch located at the intersection of railway lines, of a switch tongue associated with said switch and adapted to be urged to normal positions with respect to each line, cylinders located in juxtaposition with said switch, pistons operable in 75 said cylinders and adapted to operate against said tongue alternately, cylinders located remotely from the first named cylinders, pistons operable therein for creating air-pressure, means for operating said last named piston, means for positioning said pistons normally, an air-line communicating with each set of cylinders, and means interposed in the air-line for relieving pressure in the system.

4. A pneumatically operable railway 80 switch, consisting of a switch located at the intersection of railway lines, of a switch-tongue associated therewith and adapted to be urged to normal positions with respect to each line, cylinders located in juxtaposition with said switch, pistons operable in 85 said cylinders and adapted to operate against said tongue alternately, cylinders located remotely from the first named cylinders, pistons operable therein for creating air-pressure, means for operating said last named pistons, means for positioning said pistons normally, an air-line communicating with each set of cylinders, and means 90 interposed in the air-line for relieving pressure in the system.

5. A pneumatically operable railway 95 switch, consisting of a switch located at the intersection of railway lines, of a switch-tongue associated therewith and adapted to be urged to normal positions with respect to each line, cylinders located in juxtaposition with said switch, spring-actuated pistons operable in 100 said cylinders and adapted to operate against said tongue alternately, cylinders located remotely from the first named cylinders, spring-actuated pistons operating therein, means carried by the second named pistons for urging them to pressure-creating 105 positions, an air-line communicating with each set of cylinders, and a pressure-relieving medium suitably located in the system.

6. A pneumatically operable railway 110 switch, consisting of a switch located at the intersection of railway lines, of a switch-tongue associated with said switch and adapted to be urged to normal positions with respect to each line, cylinders located in juxtaposition with said switch, pistons operable in 115 said cylinders and adapted to operate against the tongue alternately, cylinders located remotely from the first named cylinders, pistons operable therein for creating air-pressure, means for operating the last named 120

125 pistons operating therein, means carried by

pistons, means for partially revolving said pistons, means for positioning said pistons normally, and an air-line communicating with each set of cylinders.

- 5 7. A pneumatically operable railway switch, consisting of a switch located at the intersection of railway lines, of a switch-tongue associated with said switch and adapted to be urged to normal positions with respect to 10 each line, cylinders located in juxtaposition with said switch, pistons operable in said cylinders and adapted to operate against the tongue alternately, cylinders located remotely from the first named cylinders, pistons 15 operable therein for creating air-pressure, means carried by the last named pistons and by which they may be operated, and which are so associated with the cylinders as to cause the latter to partially rotate 20 during a portion of their reciprocation, means for positioning the pistons normally, and an air line communicating with each set of cylinders.
8. A pneumatically operable railway switch, 25 consisting of a switch located at the intersection of railway lines, of a switch-tongue associated with said switch and adapted to be urged, to normal positions with respect to each line, cylinders located in juxtaposition with said switch, pistons operable in said cylinders and adapted to operate against the tongue alternately, cylinders located remotely from the first named cylinders, and which are provided with guides, pistons 30 operable therein for creating air-pressure, means for operating said last named pistons, and adapted to be controlled by said guides for partially turning the pistons, to remove the piston-operating means out of the path of means to coöperate with the piston operating means, means for positioning said pistons normally, an air-line communicating with each set of cylinders, and an interposed pressure relieving device.
- 35

and adapted to be controlled by said guides for partially turning the pistons, to remove the piston-operating means out of the path of means to coöperate with the piston operating means, means for positioning said pistons normally, and an air line communicating with each set of cylinders.

9. A pneumatically operable railway switch, 40 consisting of a switch located at the intersection of railway lines, of a switch-tongue associated with said switch and adapted to be urged to normal positions with respect to each line, cylinders located in juxtaposition with said switch, pistons operable in 45 said cylinders and adapted to operate against the tongue alternately, cylinders located remotely from the first named cylinders, and which are provided with guides, pistons operable therein for creating air-pressure, 50 means for operating said last named pistons, and adapted to be controlled by said guides for partially turning the pistons, to remove the piston-operating means out of the path of means to coöperate with the piston operating means, means for positioning said pistons normally, an air-line communicating 55 with each set of cylinders, and an interposed pressure relieving device.

Signed at Oklahoma city, in the county of 60 Oklahoma and State of Oklahoma, this 25 day of April, 1912.
